Patented Sept. 2, 1919.

UNITED STATES PATENT OFFICE.

HERBERT J. ATKINSON AND GEORGE F. CLARK, OF DENVER, COLORADO.

SPARK-PLUG.

1,315,002.

Specification of Letters Patent. Patented Sept. 2, 1919.

Application filed August 23, 1918. Serial No. 251,102.

To all whom it may concern:

Be it known that we, HERBERT J. ATKINSON and GEORGE F. CLARK, citizens of the United States, residing at the city and county of Denver and State of Colorado, have invented certain new and useful Improvements in Spark-Plugs; and we do declare the following to be a full, clear, and exact description of the invention, such as will enable others skilled in the art to which it appertains to make and use the same, reference being had to the accompanying drawings, and to the characters of reference marked thereon, which form a part of this specification.

Our invention relates to improvements in spark plugs for internal combustion engines our object being to provide a device of this character of such construction that the points or parts on opposite sides of the gap shall be kept clean automatically when the engine is in use.

It is well known that one of the serious difficulties in connection with engines of this character is due to the fouling of the points or electrodes of the spark plugs causing what is termed "missing", or the absence of explosions in the cylinders.

In our improvement the pin or rod passing through the longitudinal or axial center of the plug is divided and the insulating member is correspondingly divided, the inner member of the pin and the corresponding member of the insulating material being mounted to reciprocate, the outward movement being imparted by the compression as the piston moves toward the outer extremity of the cylinder, while the other movement is imparted by the suction or partial vacuum produced by the piston as it leaves its outermost position in the cylinder. If necessary, the action of the partial vacuum may be supplemented by a spring so arranged as to be under tension to separate the two members of the plug as soon as the compression is diminished. The rod or pin of the plug whose inner extremity forms one of the points or electrodes is arranged to pass through a perforation formed in a cleaning member mounted on the body of the plug and extending inwardly beyond the sparking position of the pin, but so arranged that its perforation receives the electrode extremity of the pin when the two members of the plug are separated. Furthermore, the pin is provided with an

enlargement a short distance beyond its electrode extremity which comes in contact with the other point or electrode member, whereby both electrodes or points are kept clean 60 or prevented from fouling during the operation of the engine.

Having briefly outlined our improvement we will proceed to describe the same in detail, reference being made to the accompanying drawing in which is illustrated an embodiment thereof. In this drawing:

Figure 1 is a central longitudinal section of the spark plug equipped with our improvement shown on a scale considerably 70 larger than normal.

Fig. 2 is an end elevation or a view looking in the direction of arrows 2, Fig. 1.

Fig. 3 is a section taken on the line 3—3, Fig. 1 viewed in the direction of the arrows. 75

Fig. 4 is a fragmentary sectional view of the spark plug similar to Fig. 1 but showing the parts of the plug in the operative or sparking position as distinguished from the non-sparking position, which is shown 80 in Fig. 1.

The same reference characters indicate the same parts in all the views.

Let the numeral 5 designate the body of the plug or the metal casing which is connected with the cylinder by means of screw threads 6 formed on the inner end of the body member. This hollow body or casing receives the insulating members 7 and 8 of the plug, these members being preferably 90 composed of porcelain, though any other suitable insulating material may, of course, be employed. The member 7 is held in place by a screw plug 9 which is threaded into the outer end of the body 5, a suitable 95 packing 10 being arranged between the inner end of the plug and the opposing shoulder of the insulating member. The insulating member 8 is mounted wholly within the hollow of the body 5, and embedded therein 100 is one member 12 of the beam or rod, its outer extremity 13 being equipped with an enlargement 14 adapted to engage the corresponding enlargement 15 formed on the inner extremity of the other member 16 of the 105 pin which is embedded in the insulating member 7. The outer extremity of the pin member 16 carries a metal member 17 which is threaded thereon to engage a contact wire 18 forming part of the circuit, the said wire 110 also resting on a metal member 19 engaging the outer extremity of the insulating part 7.

The member 12 of the pin extends inwardly beyond the body 5 its inner extremity 20 constituting an electrode or point which coöperates with an electrode 21 carried by the body 5 and also extending inwardly beyond the latter. The body member 5 is also provided with a part 22 which extends inwardly therefrom and is bent, as shown at 23, and extends laterally as shown 10 at 24, into the path of the electrode or point 20 of the pin 12, the part 24 being perforated to form a close fit for the electrode 20. This part 22 is preferably composed of metal and its function is to clean 15 the electrode 20 as the latter is thrust inwardly to its limit of movement, as illustrated in Fig. 1. Furthermore, the member 12 of the pin is provided with an enlargement 25 which when the movable member 20 of the plug is at its inward limit of movement engages the free end of the electrode 21 and performs the cleaning function.

As the movable member of the plug is mounted to reciprocate whereby it occupies 25 the position shown in Fig. 1, when the piston makes its inward stroke, and occupies the position shown in Fig. 4 when the piston makes its outward stroke, it will be seen that the electrodes are arranged in the sparking 30 relation when the piston is at its outward limit of movement and in the cleaning relation when the piston is at its inward limit of movement.

From this it will be understood that as the 35 movable member of the spark plug reciprocates, the electrodes will be kept clean or prevented from fouling due to carbon, oil or other impurities in the cylinder.

From the foregoing description the operation 40 of the device will be readily understood. The compression of the fluid in the cylinder due to the outward movement of the piston will force the movable member of the spark plug into the position, shown in Fig. 4, or so 45 that the two parts 12 and 16 of the pin are in contact to form a continuous electrical conductor, by the time the explosive mixture is properly compressed in the cylinder and the current jumping from one electrode to 50 another will produce the necessary spark for igniting the explosive mixture. Again, as soon as the piston moves inwardly the suction or partial vacuum produced will have a tendency to cause the movable member of 55 the plug to move inwardly to the position shown in Fig. 1, whereby the electrode end 20 of the pin will engage the part 22 in cleaning relation, while the enlargement 24 of the pin will engage the electrode 21 in 60 the same relation. In this way, the electrodes or metal parts of the plug which are arranged on opposite sides of the gap 26 will be kept clean at all times. In case the suction or partial vacuum due to the inward 65 movement of the piston in the cylinder is

not sufficient alone to cause the movable member to move inwardly to the position shown in Fig. 1, a spring of any suitable character may be utilized to supplement the action of the partial vacuum. In the drawing I have shown a spiral spring 27 arranged between the movable and stationary members of the spark plug, and occupying the space 28 between these members when the inner member is at its inward limit of 70 movement. When the movable member is forced outwardly to occupy the position shown in Fig. 4, whereby the two parts of the pin are brought into engagement to form a continuous conductor, the spring 27 is 75 compressed to occupy a small pocket 29 formed between the insulating parts 7 and 8 of the plug, the part 8 being recessed for the purpose, an outer part 30 of the insulating member 8 extending outwardly a short 80 distance to prevent the battering of the spring when the two members of the plug are in the sparking relation. In order to prevent undue air cushion resistance when the movable member is moving outwardly 85 under the action of compression in the cylinder, a passage 31 leading from the cavity 28 to the atmosphere is provided. Furthermore, in order to prevent obstruction to the inward movement of the movable member, a 90 passage 32 leads from the space 33 to the atmosphere.

In addition to the packing member 10 arranged between the screw plug 9 and a shoulder of the insulating member 7, a 100 similar packing member 34 is arranged between the inner extremity of the insulating part 7 and the adjacent shoulder of the metal body or casing of the plug.

Having thus described my invention, what 105 I claim is:

1. A spark plug whose insulating member is divided into two parts, and a conducting pin correspondingly divided, the parts of the pin being embedded in the respective 110 insulating parts, one of the insulating parts and its corresponding pin member being movable for electrode cleaning purposes.

2. A spark plug whose insulating member is divided into two parts, and a conducting pin correspondingly divided, the parts of the pin being embedded in the respective insulating parts, one of the insulating parts and its corresponding pin member being 115 movable for electrode cleaning purposes, the 120 plug being equipped with cleaning members arranged in suitable proximity to the electrodes.

3. A spark plug having an insulating member consisting of a plurality of parts, 125 one of said parts being movable, and a conducting pin composed of a plurality of parts, one of which is carried by and movable with the movable insulating part, said movable member being adapted to be moved auto- 130

matically in synchronism with the movements of the engine on which the plug is used.

4. A spark plug having an insulating member consisting of a plurality of parts, one of said parts being movable, a conducting pin composed of a plurality of parts, one of which is carried by and movable with the movable insulating part, and an electrode spaced from and coöperating with the movable pin part, said movable parts being adapted to be moved automatically through compression and suction in the engine on which the plug is used.

15 5. A spark plug having an insulating member consisting of a plurality of parts, one of said parts being movable, a conducting pin composed of a plurality of parts, one of which is carried by and movable with the movable insulating part, and an electrode spaced from and coöperating with the movable pin part, the plug being equipped with cleaning members arranged in suitable proximity to the electrodes.

20 6. A spark plug composed of a metal body, a divided pin, insulating members in which the parts of the pin are respectively embedded, one of the insulating members and its pin part being movable to bring the pin

parts into and out of unitary relation, said movable parts being adapted to be moved automatically through compression and suction in the engine on which the plug is used.

7. A spark plug composed of a metal body, 35 a divided pin, insulating members in which the parts of the pin are respectively embedded, one of the insulating members and its pin part being movable to bring the pin parts into and out of unitary relation, and 40 an electrode carried by the metal body and coöperating with the movable pin part to produce the spark.

8. A spark plug composed of a metal body, 45 a divided pin, insulating members in which the parts of the pin are respectively embedded, one of the insulating members and its pin part being movable to bring the pin parts into and out of unitary relation, an electrode carried by the metal body and coöperating with the movable pin part to produce the spark, and cleaning means mounted on the plug in suitable proximity to the electrode parts.

In testimony whereof we affix our signatures.

HERBERT J. ATKINSON.
GEORGE F. CLARK.
